UNITED STATES PATENT OFFICE.

HARRY GAMWELL AND CHARLES GAMWELL, OF LIVERPOOL, ENGLAND.

PREPAYMENT-METER.

No. 872,504.

Specification of Letters Patent.

Patented Dec. 3, 1907.

Application filed March 7, 1904, Serial No. 196,936.

To all whom it may concern:

Be it known that HARRY GAMWELL and CHARLES GAMWELL, both subjects of the King of Great Britain and Ireland, residing 5 at 15 Fraser street, Liverpool, England, have invented a new and useful Improvement in Prepayment Gas-Meters, of which the following is a specification.

This invention relates to a pre-payment 10 gas meter for domestic use, and consists of certain improvements in the mechanism whereby the gas inlet valve is opened by a coin which is manipulated by the purchaser and whereby such valve is closed by the 15 measuring mechanism of the meter.

The characteristic feature of the invention is that the coin—held between the finger and thumb of the purchaser—forms the 20 implement by which such valve is opened, that is the purchaser holds the coin and uses it as the implement by which to open the valve.

We are aware that a coin has heretofore 25 been employed to form an operative connection between an implement such as a crank or push-piece and the gas valve, and we desire to point out that in the present invention the coin does not form such an intermediary, but is the operative implement 30 handled by the purchaser.

In the annexed drawing Figure 1 is a plan of a "dry" gas-meter fitted with coin-freeed or operated mechanism according to this invention. Fig. 2 is a side sectional elevation 35 of such mechanism, Figs. 3 and 4 (the latter partly in section) being front and rear views, respectively, of the coin-receiving device or holder. Fig. 5 is a plan of the coin-holder and its spindle. Fig. 6 is a plan of the 40 bracket in which the coin-holder spindle is journaled. Fig. 7 is a front view of the plate journaling the end of the coin-holder spindle.

In the gas meter according to this invention illustrated in the annexed drawing the valve above referred to comprises a cylindrical case 1 communicating with the gas-inlet 2 and with the pipe 3 leading into the meter 4, respectively, the valve proper 5 having a seating in such casing and controlling such communication. The valve 5 is capable of an axial travel in the casing 1. The opening of such a valve, namely its withdrawal from its seat, or other equivalent movement, is directly performed by hand with the aid of a coin, the latter serving

as the opening or actuating implement, and the degree or distance to which the valve is opened or removed from its seat coincides with the number of coins used—separately—in thus opening the valve, as will now be described.

The valve spindle 6 is connected to a sleeve 7, the latter having an internal thread and an external pinion-wheel 8. A secondary spindle 9—in alinement with the spindle 6—bears an external thread which screws into the internally threaded sleeve 7. The outer end of said secondary spindle 9 terminates in a coin-receiving device of novel 60 form. Such device comprises a rotary half-ball or semi-spherical coin-holder 10 corresponding in diameter with the coin to be inserted. The coin-holder 10 is attached to the end of the secondary spindle 9, and 65 forms a rotary holder for the reception of the coin, whereby the latter may be used as a key by which the secondary spindle 9 may be turned in the screwed sleeve 7 of the valve-spindle 6 and so withdraw the valve 70 from its seat.

The coin-holder 10 possesses two diametrically opposite slots 11, and at its outward side 13 is concave, so that a coin (designated by the dotted line 14 in Figs. 2 and 5) inserted in one of such slots 11 projects sufficiently to be held and twisted in the finger and thumb. The coin-holder 10 end of the spindle 9 is revolubly socketed in a guard-plate 15 possessing an aperture corresponding with the concavity 13 in the coin-holder 10. Two notches 12 in the plate 15 register with the slot 11 which is for the time being horizontal, and permit the insertion of a coin 14 into the holder 10, that is 90 to say, the aperture in the guard-plate 15 is of less diameter than the coin, and the notches 12 allow the insertion of a coin into the horizontal slot 11. The edge of the coin displaces from engagement with such horizontal slot 11 four spring-detents, namely a pair of detents 16 socketed on the plate 15, and a pair of detents 17 socketed in the bracket 18, which detents normally lock the holder 10, so that the holder 10 and spindle 100 9 may then be turned one quarter-revolution. On completion of such quarter-revolution the said detents 16, 17, then engage the second and now horizontal slot 11 in the holder 10 and prevent its further rotation. The 110 coin 14 cannot then be withdrawn from the holder 10 as it has moved away from the

notches 12 in the guard-plate 15 and must therefore be relinquished and allowed to drop through the opening 19 into the coin-box 20. The coin 14 is thus used as a key 5 by which to turn the slotted ball-ended spindle 9 worming into the sleeve-ended valve-spindle 6. The pinion-wheel or teeth 8 on said sleeve 7 mesh with the teeth of a crown-wheel 21, the teeth on the sleeve 7 10 being sufficiently broad to remain in gear with the crown wheel 21 irrespective of the axial motion of the sleeve 7 and valve-spindle 6. A second crown-wheel 22— which forms the "change-wheel"—is laid on 15 the crown-wheel 21, engaging a pin 31 on the latter, and gears with a broad toothed pinion 23 which is rotated by the spindle 24, wheel 25 and worm 26, the latter being rotated through gear wheels by the registering 20 spindle 27 of the meter. Hence the sleeve 7 is held by the crown-wheel 21 while the spindle 9 is turned by the coin 14, and consequently the sleeve 7 and valve-spindle 6 are drawn axially and thus the valve 5 is 25 opened. The valve may be thus drawn outwardly in several stages by the use of successive coins, a limit to such opening movement being provided by a stop 28 on the sleeve-pinion 8 engaging another stop 29 on 30 the spindle 9, without jamming.

A non-return pawl 30, taking into the slots 11 in the coin-holder 10 prevents the latter from being turned in the wrong direction.

The valve 5 having been opened in the 35 manner above set forth, the closing action is performed by the registering train of the meter, which rotates the "change-wheel" 22 and consequently the crown-wheel 21 gearing with the pinion-teeth 8 on the internally 40 threaded end or sleeve 7 of the valve-spindle 6, which re-acting on the threaded end of the now stationary secondary spindle 9, gradually moves axially and so the valve 5 is closed.

45 The bracket 18 possesses slots 32 permitting a coin to drop out of the holder 10, and also a table 33 with a central pin, on which the crown-wheels 21, 22 rotate.

By the employment of a crown-wheel such 50 as 21 constantly in gear with the pinion teeth 8 of the sleeve 7, and by mounting upon the flat surface of such crown-wheel a "change-wheel" such as 22, which is also a crown-

wheel, it is possible, by making such change-wheels of an unvarying thickness (although 55 of varying diameter) to change such "change-wheels" without exercising the care now requisite in order that the "change-wheel" and its pinion should mesh accurately, that is to say there is no "setting-up" required, 60 one change-wheel 22 dropping into the place of the one removed.

The valve-spindle 6 and the spindle 24. pass through suitable stuffing-boxes as 65 shown.

Having now described our invention, what we claim to be new and desire to secure by Letters Patent is:—

1. In a prepayment gas meter, a revoluble spindle formed with slots to receive a coin as 70 the implement by which such coin receiver is turned, a plate journaling the end of said coin receiver and having an aperture of less diameter than the coin, said aperture having notches in its edge permitting the entry of 75 such coin into the slot in the coin receiver registering therewith, said plate operating to prevent withdrawal of the coin after the coin receiver has been turned, spring detents located on said plate and engaging the slot so 80 registering with such notches and arranged to be displaced therefrom by the coin, and a connection between said coin receiver and the valve controlling the passage of gas through the meter, whereby the rotation of 85 said coin receiver operates to open said valve.

2. In a prepayment gas meter, a revoluble spindle having a concave globular end possessing slots adapted to receive a coin as the 90 implement by which it is turned, a plate journaling the end of said coin receiver and having an aperture of less diameter than the coin, said aperture having notches in its edge for entirely uncovering said slots, a non-re- 95 turn pawl engaging such slots, and a connection between said coin receiver and the valve controlling the passage of gas through the meter, whereby the rotation of said coin receiver operates to open said valve.
